CLAIM

The ornamental design for a tool clip, as shown and described.

DESCRIPTION

FIG. 1 is a perspective view of a first embodiment of a tool clip showing our new design;

FIG. 2 is a side elevational view thereof, the opposite side being the mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of a second embodiment of a tool clip showing our new design;

FIG. 8 is a side elevational view of the embodiment of FIG. 7, the opposite side being the mirror image thereof;

FIG. 9 is a front elevational view thereof;

FIG. 10 is a rear elevational view thereof;

FIG. 11 is a top plan view thereof; and,

FIG. 12 is a bottom plan view thereof.

FIG. 1

FIG. 5

FIG. 3

FIG. 2

FIG. 4

FIG. 6

FIG. 7

FIG. 11

FIG. 9

FIG. 8

FIG. 10

FIG. 12
